AIR CONDITIONING APPARATUS

Reuben H. Anderegg, La Crosse, Wis., assignor to
The Trane Company, La Crosse, Wis.

Application September 23, 1935, Serial No. 41,767

10 Claims. (Cl. 62—117)

My invention relates to an air conditioning apparatus, particularly for railway cars, and one of the chief objects of my invention is to provide an improved apparatus to economically and efficiently extract heat from one side of an air conditioning heat cycle for use in air conditioning a railway car.

Another object of my invention is an air conditioning apparatus which can use lower head pressures in the condenser.

Another object of my invention is an improvement in extracting heat from the condenser side of a heat cycle to reduce the load on the compressor.

Another object of my invention is to control the operation of the compressor motor in co-operation with the apparatus extracting heat on the condenser side of the heat cycle.

The foregoing and many other specific features of my invention are set forth in the following specification, where I describe what I consider the preferred embodiments of my invention. These are illustrated in the accompanying drawings where—

Figure 1 is a longitudinal cross section of a railway car showing diagrammatically the arrangement of the air conditioning equipment.

Figure 2 is a plan view of the partitions in the water compartment.

Figure 3 is a cross section of Figure 2, taken on the lines 2—2.

Figure 4 is a plan view of the condenser cooling compartment.

Figure 5 is a cross section of Figure 4, taken on the lines 4—4 and showing the pump and connections in dotted lines.

Figure 6 diagrammatically shows the electrical connections between the compressor motors, thermostats and condenser cooling equipment.

Figure 7 is a plan view of condenser cooling compartment similar to Figure 4 and showing a modified form of my invention.

Referring to Figures 1 to 5, inclusive, 20 is the duct system for conveying conditioned air into outlets 21 into the car compartment 22 to be cooled. The cooling coils 25 are mounted in the top of the car and are connected with a source of cold or cooling cycle by means of the pipes 26 and 27. 28 is a filter interposed in the air inlet 29. 30 is a compressor mounted in a compartment 31 supported from the bottom 32 of the car, which compressor is operated by a motor 63. 24 is the liquid line from the compressor 30 to the wet condenser coil 34 located in the compartment 35, where the liquid or gas is cooled and then forced

through the pipe 27 through the expansion valve 36 to the coil 25.

The compartment 35 contains equipment to cool the condenser and is a metallic box capable of holding a considerable amount of water, to-wit: 5 150 gallons, and comprises side walls 39 and 41, end walls 40 and 42 and bottom 23. In the bottom of the box or compartment 35 is located a drain 33. Traversing the length and width of the compartment 35 are reinforcing bars 37 and 38, 10 respectively, which are attached to the side walls 39 and 41 and the end walls 40 and 42, at 43 and 44, 45 and 46, respectively, each of the bars being provided with a plurality of openings 47 on the bottom of the bar, so that there is formed in the 15 compartment 35 a plurality of small water compartments 48, each connected to the adjacent compartment. The height of the water is regulated so that when full it will be substantially the height of the bars 37 and 38 and that any 20 excess over that amount will flow out the air inlet 49. This air inlet opens toward the side of the car to avoid the dust and dirt of the roadbed, and across the inlet is placed an air filter 50 of conventional design and the filter is securely attached to the side wall 39 by clips or wing nuts 51 so that it can be easily removable and replaced at maintenance points to allow inspection, introduction of water and, if necessary, removal of coil. The coil 34 is a conventional fin and tube 30 type coil comprising tubes 52 and fins 53 which are rectangular in shape.

The heat exchange tubes longitudinally lay in a longitudinal plane and the fins in a vertical plane, and on the ends and sides of the coil are 35 protective and supporting casings 54 and 55, attached to which are rigid support straps 56, attached to the floor 32 of the car by removable bolts 57. When the coil 34 is mounted in the compartment 35, the tubes longitudinally will lie 40 in horizontal planes; the fins will be in vertical planes, while the bottom and top edge of the fins and the casing 52 will lie in a plane forming an oblique angle to the horizontal. Sprays 58 are connected and attached to a water supply 45 pipe 59, supported from the bottom of the car 32 by the strap 60 and in communication with the water pump 61 with an inlet pipe 62 leading to the pump from the bottom of the compartment 35. The water pump is direct connected to and 50 operated by the motor 63. The motor 63 by means of the belt 64, and pulleys 65 and 66, rotates the shaft 68 on which are mounted fans 67 with suction inlet 69 above the water level in the compartment. The fans 67 draw the air 55

through the inlet 49 past the sprays 58 and through the coil 34 in a diagonal direction; thence through the fan housing 70; then downward through a duct 71 leading downward through the 5 compartment 35 to an air outlet 72 located in the bottom of the compartment 35 so that the air is discharged toward the roadbed, and on movement of the train a slight suction will be caused by passing air upon the inlet 72, thus 10 aiding the action of the fans 67. The air outlet 72 is protected by the screen 73 to prevent the entrance of rocks and small animals and foreign material.

The sprays 58 are mounted in the compartment 35 between the filter 50 or the air inlet 49, and the coils 34, and are so set that the water will be directed in a diagonal direction and against the fins 52 and 53. The air stream passing by the wetted fins and tubes will evaporate 20 a portion of the water, thereby extracting heat from the fins and tubes in addition to the normal heat extraction caused by the passage of the air. What moisture is not evaporated will fall down into the water compartment to be repumped and 25 resprayed over the coil 34. In operation, a tank holding substantially 150 gallons will last ten to twelve hours. At maintenance points the supply can be easily replenished by removing the filter 50 and putting in water by means of a hose. At 30 the same time the coil 34 can be thoroughly flushed by the same stream of water.

Hitherto, in using dry air to cool the condenser in an air conditioning apparatus for a railway car, it has been found that approximately 8000 35 c. f. m. of dry air is required, while in using air substantially saturated or at the wet bulb temperature, only 2500 c. f. m. is required, thereby reducing materially the horsepower required for the fans.

40 Also, hitherto, in using dry air, the head pressures in the condenser were frequently approximately 275 pounds with a condensing temperature of 145 to 150° F. due to the high temperature of the air caused by reflected and radiated heat from 45 the roadbed. Frequently air temperatures of 120 to 140° F. dry bulb were encountered, resulting in a head pressure of 275 pounds and a condensing temperature of 145 to 150° F. The maximum wet bulb temperature in the United States is about 50 80° F., and using this air, to-wit: 80° F. wet bulb and 100° F. dry bulb, would produce a head pressure of approximately 150 to 160 pounds, with a condensing temperature around 100° F. This 55 results in a two-fold saving—first, a reduction in the head pressure will reduce the load on the compressor and, second, liquid with a condensing temperature of 100° will do more work than a liquid with a 150° condensing temperature when passed through the expansion valve and expanded into a gas with a required temperature of 40° F.

60 A further saving may be obtained by reducing the dry bulb and, consequently, the wet bulb temperature of the entering air by means of a coil 200 placed in the entering air. This coil is shown in Figure 7 and is connected to the water supply pipe 59 by pipe 201 at coil inlet 206. A valve 202 is interposed in pipe 59 to regulate the 65 flow of water to the coil by varying the orifice. A further valve 203 is interposed in the pipe 204 to similarly regulate the amount of spray water supplied. After going through the coil, the water is returned to the water compartment by means 70 of the pipe 205 connected to the coil outlet 207.

Assuming an air condition of 120° dry bulb, 80° wet bulb, 63° dewpoint, the lowering of the dry bulb temperature to 100° gives the following condition: 100° dry bulb, 75° wet bulb, 63° dewpoint. As the spray contacts the air, the tendency of the air is to approach the wet bulb, and the tendency of the water also is to approach the temperature of the wet bulb.

Thus, with a wet bulb of 80° F., the temperature of the water returned to the tank would approach 10 80° F., which would be the temperature of the water entering the coil 200; and with entering air with a dry bulb of 120° F., wet bulb 80° F., and dewpoint 63° there would be obtained a leaving air temperature of 100° dry bulb, 75° wet bulb and 15 63° dewpoint. The tendency of the spray now is to further condition the air to a lower wet bulb condition than could be obtained without the use of the coil 200, and thus effect further economies in compressor load, head pressures and condensation temperatures as explained above.

20 Referring to Figure 6 showing the controls for the equipment hereinbefore set forth, numeral 100 represents a compressor motor, 101 a power line, 102 a return power line, 103 a magnetic starter 25 in line 101, 104 a resistance starter. Line 102 goes through magnetic starter and resistance starter 104 to compressor motor 100. 105 represents a part of line 102 from magnetic starter 103 to time switch 106, whose function is to close the circuit 30 through the magnetic starter, which starts the compressor motor. This time switch is controlled by the pump pressure switch 107, through the lines 108 and 110 and car thermostat switch arm 112.

35 Interposed in the line 108 is the pump pressure switch 107. Line 109 is a continuation of line 108, and the line 109 runs to a car thermostat 111, and line 110 runs from the car thermostat as a return power line. 112 is a switch arm for the car thermostat so that when the temperature 40 rises the switch arm 112 completes the circuit between lines 109 and 108 and starts the time switch 106.

45 Another power circuit comprising lines 113 and 114 lead from the time switch, and interposed in the line 114 is a holding coil 115 for the magnetic 50 starter 116 for the evaporator condenser motor 63, which is connected with the magnetic starter 116 by continuation of the power lines 117 and 114 so that when the holding coil is energized by closing of thermostat 111, the magnetic starter 116 starts the evaporator condenser motor 63.

55 A mercury switch 118 is located in the bottom of the tank 35 and is controlled by a float responsive to the height of the water in the tank 35 so when the water is low enough to allow the float to drop, the switch arm 119 opens.

60 The mercury switch 118 is a double pole switch comprising arms 119 and 119A. The arm 119 is connected by the line 120 leading from the holding coil 115 and the line 121 to the thermostat 111; thence by the line 123 as a return power line, and the switch arm 119A is connected to the line 110A, which is a return power line, and also by line 110, which is connected to the thermostat 111. When the switch 118 is closed the circuits will be closed and the motor 63 will operate; and when the switch 118 is open due to the fall of the water in the tank, the circuit formed by the lines 120, 121 and 123 will be broken and the circuit formed 70 by the line 110A, 110, 109, holding coil 122 and line 108 will be broken. This will cause the time switch 106 to finally open as hereinafter set forth and break the connection in the line 114A, thus taking the energy from the holding coil 115. 75

breaking the circuit and stopping the motor 63. Thus, when the water in the tank 135 reaches a predetermined level, the entire mechanism will cease to operate.

- 5 In the pressure switch 107 is the arm 124, and when the switch is closed, together with the closing of the thermostatic switch arm 112, the circuit represented by the lines 108, 109, 110 energizes the coil 122, causing time switch arms 125 to rotate into a position which closes the circuit represented by lines 105 and 126 energizing the coil 127 in the magnetic starter 103, which starts the compressor motor 100, which continues to run as long as the line is closed. When the switch 15 arm 124 is open, the circuit is broken, coil 122 is de-energized, thereby causing the time switch 106 to break the circuit to the compressor motor, thereby stopping it.

The time switch 106 is composed of two movable switch arms 125 and 127 so that when the coil 122 is energized, the arms 125 and 127 move to the left over an arc and contact the points 129 and 128, respectively, of the lines 126 and 105, respectively. And when coil 122 is de-energized, the 25 switch arms move to the right, breaking the circuit formed by the lines 126 and 105.

On switch arm 127 is also a contact point 130, interconnected to line 114 at contact point 131. As switch arms 125 and 127 move to the left, 30 contact point 130 is brought in contact with arc 132, which completes the circuit through power line 113 and return power line 114 through holding coil 115 of the magnetic starter 116.

Contact point 130 maintains contact with arc 35 132 as long as switch arms 125 and 127 are moving to left and also maintains contact when switch arms 125 and 127 make contact with points 129 and 128, respectively.

When time switch arms 125 and 127 have 40 moved to the left and closed contacts between switch arms 125 and 127, and contacts 129 and 128 respectively, any breaking of contact between switch arm 112 of car thermostat 111 and line 121 because of lowering of car temperature below 45 setting of thermostat, or any break in contact between switch arm 112 and line 110 because of lowering of car temperature below setting of thermostat, or any break in contact between switch arm 124 and line 108 in pressure switch 50 107 because of insufficient pressure in discharge line of pump, or any break between switch arm 119 and line 120 in mercury switch 118 will de-energize coil 122 in time switch 106, causing switch arms 125 and 127 to move to the right, thus 55 breaking contact with contact points 129 and 128, respectively, and stopping compressor motor 100 by opening magnetic starter 103.

As switch arms 127 and 125 move to right, contact point 130 will maintain contact with arc 60 132 until contact arms 125 and 127 are in the extreme position at the right, when contact will be broken between contact point 130 and arc 132. Thus, holding coil 115 will remain energized through power lines 114 and 113 and contact point 130 and arc 132 until switch arms 125 and 127 are in the extreme right position, when coil 115 will be de-energized due to breaking of contact between point 130 and arc 132. This 65 magnetic starter 116 will continue to maintain 70 in operation the evaporator condenser motor 63 after compressor motor 100 is stopped for the time required for switch arms 125 and 127 to move from extreme left position to extreme right position, where contact between points 130 and 75 132 is broken, coil 115 is de-energized and evapo-

rator condenser motor 63 is stopped. As thermostat switch arm 112 again makes contact with lines 110 and 121 due to increase in car temperature, holding coil 115 of magnetic starter 116 will be energized starting evaporator condenser 5 motor 63, which will close pressure switch arm 124 and line 108, thus energizing coil 122 which will cause switch arms 125 and 127 to move to the left and start compressor motor 100 as described above.

In case of shortage of water in evaporative condenser, switch arm 119 will not make contact with line 120 and will not allow car thermostat to start equipment because current 120 to 114 through holding coil 115 is broken.

Line 133 is a power line interconnected to line 101 in magnetic switch 103 and resistances 134, 135 and 136 respectively. Resistances 134, 135 and 136 are connected in series by means of lines 137 and 138, respectively.

Line 138 is a continuation of power line 133 connecting resistance 136 to the field coil 140 of compressor motor 100.

Line 141 is a return power line from field coil 140 to continuation of return power line 102.

By means of the thermostats 142 and 143 and 144, and relay switches 145, 146 and 147, the resistances 134, 135 and 136 are inserted in power lines 133 and 139, either singly or in multiple to vary the speed of compressor motor 100 as follows.

Thermostat 142 is connected to power line 148, which is a branch of line 133, by means of line 149 through holding coil 150 of relay switch 145. A return power line 151 runs from thermostat 35 switch arm 152 to return power line 126.

Line 153 is a continuation of power line 148 through relay switch 145 to line 139.

Thermostat 143 is connected to power line 148 by means of line 154 through holding coil 155 40 of relay switch 146. The switch arm 156 of thermostat 143 is connected by means of line 157 to return power line 151. Line 158 connects power line 148 to line 138 through relay switch 146.

Thermostat 144 is connected to power line 148 by line 159 through holding coil 160 of relay switch 147. Thermostat switch arm 161 is connected to return power line 151 by means of line 162.

Line 163 connects power line 148 to line 137 through relay switch 147.

In order to clarify control diagram, thermostats 142 and 143 and 144 have been shown as separate thermostats. In actual practice thermostats 142, 143 and 144 would all be contained in one instrument.

Thermostats 142, 143 and 144 are of the heating type closing the circuit on lowering temperature and opening the circuit on rising temperature.

Thermostats 142, 143 and 144 are set to operate in sequence—that is, thermostat 142 is set to open first on rising temperature and cut out last on lowering temperature. Thermostat 143 65 will open second on a rising temperature and close second on lowering temperature. Thermostat 144 will open last on rising temperature and close first on lowering temperature.

Thus, when starting up with high temperatures 70 in car, thermostats 142 and 143 and 144 will all be in the open circuit position. Coils 150 and 155 and 160 will not be energized and relay switches 145, 146 and 147 will be open allowing all current from power line 133 to flow through resistances 75

134, 135 and 136, and to the field coil 140 thus decreasing the current to field coil 140 and increasing the speed of the motor 100 and compressor 30.

5 164 is a starting shorting switch connected from line 133 by line 165 to return power line 139 by line 166. This starting switch is mechanically connected with resistance starter 104 by arm 167 so that in starting, contact arm 168 will 10 complete circuit through switch 164 and through starting coil 104, thus starting compressor motor 100 at same speed through all starting cycles. When compressor motor gets up to running speed, contact arm 168 is disconnected by mechanical arm 167 attached thereto, through resistance starter 104, exercising a magnetic attraction on the arm 167 similar to a solenoid. Thus, when the switch 164 is open, the speed of the compressor motor is dependent upon the action 15 of the thermostats 142, 143 and 144.

While I have described the foregoing preferred embodiments of my invention, I contemplate that many changes may be made without departing from the scope or spirit of my invention.

25 I claim:

1. In an air conditioning apparatus for a railway car, the combination of a heat exchange cycle, with the evaporator side of said cycle situated within the car to condition the air therein, 30 a compressor in said cycle delivering gas under pressure to the condenser side of said cycle, housed within a compartment beneath said car, said compartment having a water chamber, an air inlet, a removable filter in said air inlet, an 35 air outlet and means to draw air from said inlet to outlet, a condenser coil interposed in said condenser side and in the path of said air, sprays positioned between said air inlet and said condenser coil, conduits connecting said sprays with the bottom of said water chamber, a pump in one 40 of said conduits, a pressure switch in said conduit controlling the operation of said compressor, means to draw air from said inlet through said sprays and coil to said outlet.

45 2. In an air conditioning apparatus for a railway car, the combination of a heat exchange cycle, with the evaporator side of said cycle situated within the car to condition the air therein, a compressor in said cycle delivering gas under 50 pressure to the condenser side of said cycle, housed within a compartment beneath said car, said compartment having an air inlet and an air outlet and fan means to draw air from said inlet to outlet, a condenser coil interposed in said condenser side and in the path of said air, sprays positioned between said air inlet and said condenser coil, conduits connecting said sprays with the bottom of said water chamber, a pump in one of said conduits, a pressure switch in said 55 conduit, means responsive to said pressure switch controlling the operation of said compressor.

3. In an air conditioning apparatus for a railway car, the combination of a heat exchange cycle, with the evaporator side of said cycle situated within the car to condition the air therein, a compressor in said cycle delivering gas under pressure to the condenser side of said cycle, housed within a compartment beneath said car, said compartment having an air inlet and an air 60 outlet and fan means to draw air from said inlet to outlet, a condenser coil interposed in said condenser side and in the path of said air, sprays positioned between said air inlet and said condenser coil, means to draw air from said inlet 65 through said sprays and coil to said outlet, sin-

gle means to operate both said pump and said fan, means responsive to the height of the water in water chamber controlling the operation of said fan and pump.

4. In an air conditioning apparatus for a railway car, the combination of a heat exchange cycle, with the evaporator side of said cycle situated within the car to condition the air therein, a compressor in said cycle delivering gas under pressure to the condenser side of said cycle, 10 housed within a compartment beneath said car, said compartment having an air inlet and an air outlet and water chamber therein, a condenser coil interposed in said condenser side and in the path of said air, sprays positioned between said air inlet and said condenser coil, conduits connecting said sprays with the bottom of said water chamber, a pump in one of said conduits, fan means to draw air from said inlet through said sprays and coil to said outlet, means responsive to air in said car controlling the operation of said compressor, means to continue the operation of said pump a predetermined length of time after said compressor has stopped, whereby the pressure in said condenser is decreased. 25

5. In an air conditioning apparatus for a railway car, the combination of a heat exchange cycle, with the evaporator side of said cycle situated within the car to condition the air therein, a compressor in said cycle delivering gas under pressure to the condenser side of said cycle, 30 housed within a compartment beneath said car, said compartment having an air inlet and an air outlet and water chamber therein, a condenser coil interposed in said condenser side and in the path of said air, sprays positioned between said air inlet and said condenser coil, conduits connecting said sprays with the bottom of said water chamber, a pump in one of said conduits, fan means to draw air 35 from said inlet through said sprays and coil to said outlet, means responsive to air in said car controlling the operation of said compressor, means to insure the operation of said pump a predetermined time before the compressor 40 starts and after it stops, whereby the pressure in said condenser is decreased.

6. In an air conditioning apparatus for a railway car, the combination of a heat exchange cycle, with the evaporator side of said cycle situated within the car to condition the air therein, a compressor in said cycle delivering gas under pressure to the condenser side of said cycle, 50 housed within a compartment beneath said car, said compartment having an air inlet and an air outlet and water chamber therein, a condenser coil interposed in said condenser side and in the path of said air, sprays positioned between said air inlet and said condenser coil, conduits connecting said sprays with the bottom of said water chamber, a pump in one of said conduits, means to draw air 55 from said inlet through said sprays and coil to said outlet, means to stop said compressor responsive to the height of water in said water compartment.

7. In an air conditioning apparatus for a railway car, the combination of a heat exchange cycle, with the evaporator side of said cycle situated within the car to condition the air 70 therein, a compressor in said cycle delivering gas under pressure to the condenser side of said cycle, housed within a compartment beneath said car, said compartment having an air inlet and an air outlet and fan means to draw 75

air from said inlet to outlet, a condenser coil interposed in said condenser side and in the path of said air, sprays positioned between said air inlet and said condenser coil, means to draw air from said inlet through said sprays and coil to said outlet, single means to operate both said pump and said fan, and means to pre-cool said air before entering said sprays.

8. In an air conditioning apparatus for a railway car, the combination of a heat exchange cycle, with the evaporator side of said cycle situated within the car to condition the air therein, a compressor in said cycle delivering gas under pressure to the condenser side of said cycle, housed within a compartment beneath said car, said compartment having an air inlet and an air outlet and water chamber therein, a condenser coil interposed in said condenser side and in the path of said air, sprays positioned between said air inlet and said condenser coil, conduits connecting said sprays with the bottom of said water chamber, a pump in one of said conduits, fan means to draw air from said inlet through said sprays and coil to said outlet, and means to start the operation of the fan means and pump before the compressor starts to decrease the pressure in said condenser.

9. In an air conditioning apparatus for a railway car, the combination of a heat exchange cycle, with the evaporator side of said cycle situated within the car to condition the air therein, a compressor in said cycle delivering gas under pressure to the condenser side of said cycle, housed within a compartment beneath said car, said compartment having an air inlet and an air outlet and water chamber therein, a condenser coil interposed in said condenser side and in the path of said air, sprays positioned between said air inlet and said condenser coil, conduits connecting said sprays

with the bottom of said water chamber, a pump in one of said conduits, means responsive to the height of the water in the water chamber controlling the operation of said fan means and pump.

10. In a cooling system for railway cars, a water compartment mounted upon said car and adapted to be filled with water to a level permitting air circulation therethrough, an air inlet in said compartment, an air pump within said compartment for drawing air therethrough and exhausting it therefrom, a motor for driving said air pump, a water pump also driven by said motor, adapted to draw water from a low point in said compartment and discharge it as spray in the air space therein, a condenser coil located in said air space in the path of air drawn therethrough and of the spray so discharged by said water pump, a float operated switch in said compartment for controlling said pump motor in accordance with the water level, a pressure operated switch for said motor controlled by the pressure of water circulated by said pump, and a thermostat in circuit with said pump motor for controlling the operation of the same in accordance with the temperature requirements of the car to be cooled, a compressor motor controlled by a time switch in circuit with said pump motor for actuating the compressor of a refrigerating apparatus carried by the car, said time switch serving to close the compressor motor circuit after the pump motor circuit has been completed by closing of the aforesaid switches in circuit therewith, and adapted to be opened when contact is broken by any of said switches or by said thermostat, prior to deenergization of the said pump motor circuit and cessation of pump motor operation.

REUBEN H. ANDEREGG.
